Assistant Examiner — Devin Kelly

(57) **CLAIM**

The ornamental design for a charger, as shown and described.

DESCRIPTION

FIG. 1 is a front, bottom perspective view of a charger showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, top perspective view thereof; and,

FIG. 9 is a perspective view thereof, showing the charger in an open state of use.

The broken lines in the drawings depict portions of the charger that form no part of the claimed design.

1 Claim, 9 Drawing Sheets
